(57) **CLAIM**

The ornamental design for a rice cooker lid, substantially as shown and described.

DESCRIPTION

FIG. 1 is a perspective view of a rice cooker lid according to the design, with example environmental features with which the design may be used (a pan) shown in broken lines.
FIG. 2 is a perspective view of the rice cooker lid of FIG. 1.
FIG. 3 is a top view of the rice cooker lid of FIG. 1.
FIG. 4 is a bottom view of the rice cooker lid of FIG. 1.
FIG. 5 is a front view of the rice cooker lid of FIG. 1.
FIG. 6 is a rear view of the rice cooker lid of FIG. 1.
FIG. 7 is a left side view of the rice cooker lid of FIG. 1; and,
FIG. 8 is a right side view of the rice cooker lid of FIG. 1.
Portions shown in broken lines are for illustrative purposes only and form no part of the claimed design.
